US00D921204S

(12) **United States Design Patent** (10) Patent No.: **US D921,204 S**
(45) Date of Patent: **** Jun. 1, 2021**

(54) **HEALTH MONITORING APPARATUS**

(71) Applicant: **RDS**, Strasbourg (FR)

(72) Inventors: **George Stefan Golda**, El Granada, CA (US); **Sam Eletr**, Paris (FR); **Bruce O'Neil**, Greenbrae, CA (US); **Juan Carlos Beltran**, Redwood City, CA (US); **Mark P. Marriott**, Palo Alto, CA (US)

(73) Assignee: **RDS**, Strasbourg (FR)

(**) Term: **15 Years**

(21) Appl. No.: **29/699,500**

(22) Filed: **Jul. 25, 2019**

(56)

(57) **CLAIM**

The ornamental design for a health monitoring apparatus, as shown and described.

DESCRIPTION

FIG. 1 is an isometric view of a health monitoring apparatus according to the present design;

FIG. 2 is a first side elevational view thereof;

FIG. 3 is a second side elevational view thereof;

FIG. 4 is a front elevational view thereof;

FIG. 5 is a rear elevational view thereof;

FIG. 6 is a top plan view thereof; and,

FIG. 7 is a bottom view thereof.

The broken lines depict portions of health monitoring apparatus that form no part of the claimed design; the broken lines form no part of the claimed design.

1 Claim, 5 Drawing Sheets

Related U.S. Application Data

application No. 15/192,714, filed on Jun. 24, 2016, now Pat. No. 10,244,949, which is a continuation-in-part of application No. 14/565,415, filed on Dec. 9, 2014, and a continuation-in-part of application No. 14/565,414, filed on Dec. 9, 2014, now Pat. No. 10,080,527, and a continuation of application No. 14/565,412, filed on Dec. 9, 2014, now Pat. No. 9,782,132, and a continuation-in-part of application No. 14/565,413, filed on Dec. 9, 2014, and a continuation-in-part of application No. 14/565,412, filed on Dec. 9, 2014, now Pat. No. 9,782,132, and a continuation of application No. PCT/US2013/063748, filed on Oct. 7, 2013, and a continuation-in-part of application No. 13/837,748, filed on Mar. 15, 2013, now Pat. No. 10,413,251, and a continuation of application No. 13/837,748, filed on Mar. 15, 2013, now Pat. No. 10,413,251.
